UNITED STATES PATENT OFFICE

110,697

DESIGN FOR A BALANCING ATTACHMENT FOR A PISTOL

Richard S. Havourd, Wethersfield, Conn., assignor to Colt's Patent Fire Arms Manufacturing Company, Hartford, Conn., a corporation of Connecticut

Application April 8, 1938, Serial No. 76,388

Term of patent 14 years

To all whom it may concern:

Be it known that I, Richard S. Havourd, a citizen of the United States, residing at Wethersfield, in the county of Hartford and State of Connecticut, have invented a new, original, and ornamental Design for a Balancing Attachment for Pistols, of which the following is a specification, reference being had to the accompanying drawing, forming part thereof.

Of the drawing:

Fig. 1 is a side elevational view of the balancing attachment.

Fig. 2 is a front elevational view of the attachment shown in Fig. 1.

Fig. 3 is a rear elevational view of the attachment shown in Fig. 1.

I claim:

The ornamental design for a balancing attachment for a pistol, as shown.

RICHARD S. HAVOURD.
